UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEEL AND METHOD OF OPERATING THEREON.

Application filed October 29, 1921. Serial No. 511,377.

This invention relates to heels and methods of operating thereon and has particular reference to heel attaching. For purposes of illustration I have chosen to show 5 the invention herein as applied to the attachment of a multi-section heel such as a so-called double decked heel, a rubber half heel attached to a leather or leatherboard base, or the like, but it is apparent that, in 10 certain of its aspects, the invention is equally applicable to the attachment of a whole or one piece heel to the heel seat of a shoe.

In attaching multi-section heels two methods of operation are in common use. 15 According to the first of these methods the base section, or deck, is attached to the heel seat of a shoe by one operation of the heel attaching machine, and the second section or deck is attached to the base, and the shoe, by a second heelng machine operation, 20 usually performed by a separate machine. According to the other method the sections or decks of the heel are assembled in their proper relation to each other and usually 25 temporarily secured together before the heel is placed upon the shoe. The assembled multi-section heel is then placed upon the heel seat of a shoe and secured thereto by a single operation of the heel 30 attaching machine. In attaching a whole heel, the heel is located upon the heel seat of a shoe and, of course, attached by a single nailing operation. Regardless of 35 which of these methods is employed, it is necessary to register the top section of the heel with respect to the base, or the heel with respect to the heel seat, before they 40 are attached together, and the principal object of the present invention is to provide improved means for easily and effectively securing this register of the parts with exactness.

To this end, the heel or heel section and the support to which it is to be attached are 45 so formed with respect to each other as to co-operate in locating one upon the other, and a feature of the invention resides in the provision of readily removable means upon at least one of the parts for facilitating the registering of two engaging parts. 50 This means, in the case of a leather or leatherboard base intended for use, for example, with a rubber half heel, is preferably embodied in a peripheral flange projecting from the heel engaging face of the 55

base section and virtually providing a recess of substantially the same size as the heel to be superposed upon the face. A projection, such as that referred to, can, advantageously, be formed upon the base in the usual 60 molding operation in the heel compressor at no extra cost, and it is not necessary that the size of the base exceed that of the top section of the heel by an amount more than sufficient to provide the necessary amount 65 of material for the usual heel trimming operation. Furthermore, when the base is, as usual, trimmed flush with the remainder of the heel, after the completion of the heel and its attachment to the shoe, or, in the 70 case of a whole heel when the heel seat is trimmed flush with the heel or the heel and heel seat are trimmed together, the registering flange or projection is completely removed, leaving no trace of its existence. 75

In another aspect of the invention, a novel method is provided, which comprises molding a flange around the curved edge of the outer face of a heel base section, placing a heel top section within the flange upon 80 the base section, securing the two sections together, and then trimming off the flange.

When the heel sections are assembled off the shoe the flange may be trimmed off 85 either prior or subsequent to the attachment of the heel to the shoe. When the heel sections are assembled upon the shoe the heel attaching nails are driven and then the trimming operation is performed. 90

Further features and advantages of the invention will be appreciated and understood from reading the following detailed description of one embodiment thereof in connection with the accompanying drawings, in which

Fig. 1 shows a rubber half heel and a leather or leatherboard base embodying the invention, ready to be assembled;

Fig. 2 is a cross-sectional view of the 100 same parts assembled in register with each other;

Fig. 3 shows a heel attached to a shoe and partly trimmed; and

Fig. 4 illustrates a modified form of heel 105 base.

Referring now to the drawings, 10 indicates a rubber half heel of a well known type and 12 indicates a base section which may consist of leather, leatherboard or any 110

suitable equivalent, non-metallic material. A flange 14 projects from the heel supporting face of the heel base 12 in a direction normal thereto and, in the form of the invention illustrated in Figs. 1 and 3 extends around the curved sides and back of the heel. This flange or projection 14 may be integral with the heel base and may conveniently be formed thereon, at no expense, 10 in the compressing or molding operation to which such heel bases are usually subjected prior to their attachment to shoes.

The space within the flange 14 virtually forms a cavity which is of substantially the 15 same size as the rubber heel 10. By the aid of the flange 14 the heel section 10 is easily positioned upon the supporting base 12 in exact register therewith with the flange engaging the periphery of the rubber heel. 20 The relation of the parts when assembled, is clearly shown in Fig. 2 where the dotted lines 16 indicate the rubber heel, which is usually slightly curved in cross-section, as it is when it is brought into engagement of 25 the base 12 and the solid lines indicate the rubber heel after it has been flattened down upon the base. The parts may be assembled and secured together in the relation shown in Fig. 2 and the heel thus produced 30 may then be attached to the shoe at a single operation, or the base 12 may first be attached to the shoe and then the heel section 10 may be registered and attached at a subsequent operation. In either event the resulting product will appear as shown in 35 Fig. 3, in which 18 indicates the upper and 20 the outersole at the heel end of a shoe. If the heel to be attached is a whole heel 40 of rubber or other material, the projection 14 is, of course, formed upon the heel seat portion of the outersole 20 which becomes the immediate support for the heel.

In Fig. 3 the rear portion of the heel supporting parts is shown at 22 trimmed 45 flush with the rubber section 10 and this trimming will, of course, be carried completely around the sides in finishing the product. In this trimming operation the flange or projection 14, which no longer has 50 any purpose for existence, is completely removed. In order to provide the flange 14 the supporting part with which the upper heel section 10 is to be registered must be slightly larger than the said section but the 55 excess in size need be no more than is required to provide the stock necessary for the usual heel trimming and finishing operations.

It is not essential that the flange 14 extend uninterruptedly around the periphery of the member 12, and Fig. 4 shows a modified form of the invention in which three 60 separated projections 24 are provided for the purpose of facilitating the registering of the parts. It will, of course, be under-

stood that the invention is not limited to a registering projection or projections of any particular size or shape, the chief essential being that it or they shall be easily removable after the parts have been brought into proper register with each other.

Having described my invention, what is claimed as new and desired to be secured by Letters Patent is:—

1. A non-metallic, unfinished base section 75 for heels which is larger than its finished size and the heel to be superposed upon it, and is provided with means for mechanically facilitating the registering of the heel with the base.

2. A base section for heels which is larger than the heel to be superposed upon it and is provided with means for facilitating the registering of the heel with the base, said means being constructed and arranged to be removed in a subsequent operation.

3. A base section for heels which is provided with means for facilitating the registering of the heel with the base, said means being constructed and arranged to be removed subsequently to the registering operation.

4. A non-metallic shoe part to which a heel may be attached, provided with means for facilitating the location of the heel in a predetermined position upon said shoe part, said means being thereafter readily removable.

5. A base section for heels which is provided with means for engaging the periphery of a heel to be registered with the base, said means being removable prior to completion of the heel.

6. A non-metallic base section for heels which is larger than the heel to be superposed upon it and is provided with register facilitating means for engaging the periphery of the heel, said means being removable by a trimming operation subsequent to the registering of the heel with the base.

7. A non-metallic base section for heels which is larger than the heel to be superposed upon it and provided with a member projecting from its heel engaging face, said member being arranged to engage the periphery of a heel superposed upon the base.

8. A non-metallic base section for heels, having a flange projecting from its heel engaging face to provide a recess of substantially the same size as the heel to be superposed upon the base, said flange being removable by a trimming operation.

9. A molded, non-metallic support for heels, having an integral flange projecting from its heel engaging face, said flange being removable in the usual heel trimming operation.

10. A construction for the heel end of a shoe comprising a heel member and a supporting member for the heel member, said

supporting member being provided with means for facilitating the registering of the heel member therewith, said means being readily removable after the parts are assembled.

11. A step product comprising a non-metallic heel base having an upwardly projecting heel-registering flange at its periphery, and an upper heel section, having its 10 edge exposed, superposed upon the base and registered therewith by engagement of the flange with its periphery.

12. That method of operating upon a multi-section heel which comprises molding a 15 flange around the curved edge of the outer

face of a heel base section, placing a heel top section within the flange upon the base section, securing the two sections together, and then trimming off the flange.

13. That method of operating upon a multi-section heel which comprises building a heel base section of leather, molding a flange around the curved edge of said base section, placing a rubber top section within the flange upon the base section, attaching the 20 25 assembled heel to a shoe, and then trimming off the flange.

In testimony whereof I have signed my name to this specification.

THOMAS LUND.
